UNITED STATES PATENT OFFICE.

LEO THOMAS DWYER, OF FAIRFIELD, ILLINOIS, ASSIGNOR TO SEXTON MFG. CO., OF FAIRFIELD, ILLINOIS.

UNION GARMENT.

1,381,066.

Specification of Letters Patent.

Patented June 7, 1921.

Application filed May 18, 1920. Serial No. 382,494.

To all whom it may concern:

Be it known that I, LEO THOMAS DWYER, a citizen of the United States, and a resident of Fairfield, in the county of Wayne and 5 State of Illinois, have invented a new and Improved Union Garment, of which the following is a full, clear, and exact description.

The invention relates to wearing apparel 10 for boys and girls, and its object is to provide a new and improved union undergarment arranged to give the user the desired freedom in the movement of the body and without danger of unduly straining or tearing 15 the garment.

Another object is to provide a desired suitable support for a hose supporter.

Another object is to prevent the user's 20 body from being exposed at the usual side openings while the garment is worn.

Another object is to provide a union undergarment having bloomers for girls.

With these and other objects in view, the 25 invention consists of certain novel features of construction as hereinafter shown and described and then specifically pointed out in the claims.

A practical embodiment of the invention is represented in the accompanying drawings forming a part of this specification, in 30 which similar characters of reference indicate corresponding parts in all the views.

Figure 1 is a front perspective view of the 35 union undergarment as arranged for and worn by a girl;

Fig. 2 is a rear perspective view of the same;

Fig. 3 is an enlarged side elevation of a 40 portion of the union undergarment with one corner of the sanitary flap in open position;

Fig. 4 is an enlarged cross section of a portion of the union undergarment, the section being on the line 4-4 of Fig. 2;

Fig. 5 is a similar view of a portion of the 45 union undergarment and showing more particularly one of the tabs for engagement by a hose supporter;

Fig. 6 is a similar view of a portion of 50 the union undergarment on the line 6-6 of Fig. 1;

Fig. 7 is an enlarged sectional plan view of the hose supporter tab on the line 7-7 of Fig. 3;

Fig. 8 is an enlarged side elevation of a 55

portion of the neck opening with part broken out;

Fig. 9 is a front perspective view of the union undergarment as arranged for and worn by a boy;

Fig. 10 is a rear perspective view of the same;

Fig. 11 is an enlarged side elevation of a portion of the union undergarment with one corner of the sanitary flap in open position; and

Fig. 12 is an enlarged perspective view of one of the adjustable shoulder straps.

The body of the union undergarment is made of a woven fabric and comprises in 70 its general construction a waist 20 and drawers or bloomers 21 connected with each other by a waistband 22. The waist 20 is provided with adjustable shoulder straps 23 to fit boys or girls of different build, and the 75 waist is also provided with reinforcing straps 24 at the front and back. The back of the waist 20 is provided at the corresponding back portion of the waistband 22 with a depending elastic band 30, preferably of a knitted material, and to the lower edge of this band 30 is secured a fly 31 having its sides 32 extending below the bottoms of the usual side openings 33 formed at the drawers or bloomers 21 by the usual 80 back flap 40 provided at its upper edge with buttonholes 41 adapted to be fastened to buttons 42 secured to the fly 31. By the arrangement described the body of the user 85 is not visible at the openings 33 as such opening is closed by the enlarged side portions 32 of the fly 31 at the time the garment is worn and the sanitary flap 40 is in closed position.

From the waistband 22 depend narrow 95 tabs 50 carrying buttons 51 for supporting an outer garment such as a skirt for a girl or pants for a boy. At the waistband 22 adjacent the side openings 33 and overlying the front of the drawers or bloomers 21 are 100 arranged tabs 60, each provided in its upper portion but below the waistband 22 with eyelets 61 for engaging a safety pin for attaching the upper end of a hose supporter to the undergarment. The hose supporter extends through registering buttonholes 62 and 63, of which the buttonhole 62 is formed in the tab 60 and the buttonhole 63 is formed in the drawers or bloomers 21 (see Fig. 5) to allow of passing the upper portion of the 105 110

hose supporter from within the drawers or bloomers 21 through the registering buttonholes 63, 62 to the outside of the tab 61 to be engaged with the safety pin extending through the eyelets 61. The buttonhole stitches 64 are common to both registering buttonholes 62, 63 thus securing the lower portion of the tab 60 to the drawers or bloomers 21. In practice, each tab 60 is made of a single piece of material having the sides folded inward, after which the piece is doubled up to provide an exceedingly strong tab, as will be readily understood by reference to Figs. 5 and 7. It is understood that the upper end of each tab 60 is attached by stitches 65 to the waistband 22, the stitches also serving to attach the lower portion of the waistband 22 to the lower end of the waist 20 (see Fig. 5). A second row of stitches 66 attaches the upper edge of the waistband 22 to the waist 20.

In order to provide an exceedingly strong and durable neck opening and armholes, each is preferably constructed as follows, special reference being had to Fig. 8: The raw edge of the woven fabric of which the garment is made is provided with over-edging stitches 70, and this raw edge and the stitches 70 are inclosed by a bias binding 71 fastened in place by stitches 72 located in the rear of the over-edging stitches 70. By this arrangement the wall of the neck opening or that of either armhole is rendered exceedingly strong and durable and the binding is not liable to tear out of the raw edge, which latter is reinforced by the over-edging stitches 70.

From the foregoing it will be seen that the union undergarment is exceedingly strong and durable and allows the user the desired freedom in the movement of the body with-

out danger of unduly straining or tearing the garment.

The union undergarment for girls is provided at the legs with a suitable elastic to hold the bloomers in place.

Having thus described my invention, I claim as new and desire to secure by Letters Patent:

1. In a union undergarment, comprising a front, legs, an upper back portion and a sanitary flap forming side openings with the said legs, said front having button holes adjacent the openings, tabs attached to the said front at the waist line thereof adjacent the said side openings and extending over the button holes of the front, each tab being adapted to support a garter attaching means and each tab having a buttonhole registering with the buttonhole in the said front for the passage of a hose supporter from within the garment to be fastened to the tab by the said garter attaching means.

2. In a union undergarment, comprising a front, legs, an upper back portion and a sanitary flap forming side openings with the said legs, said front having button holes adjacent the openings, tabs attached to the said front at the waist line thereof adjacent the said side openings and extending over the button holes of the front, each tab having at its upper portion a pair of spaced eyelets adapted to be engaged by a safety pin and each tab having at its lower portion a buttonhole registering with the buttonhole in the said front for the passage of a hose supporter from within the garment to be fastened in place by the said safety pin, the buttonhole stitches being common to both registering buttonholes and fastening the lower portion of the tab to the front.

LEO THOMAS DWYER.
